UNITED STATES PATENT OFFICE.

EBER C. BYAM, OF ROCHESTER, NEW YORK, ASSIGNOR OF TWO-THIRDS TO
JOHN A. STEWART AND JAMES S. BAKER, BOTH OF SAME PLACE.

SASH-LIFT.

SPECIFICATION forming part of Letters Patent No. 363,726, dated May 24, 1887.

Application filed April 16, 1887. Serial No. 235,013. (No model.)

To all whom it may concern:

Be it known that I, EBER C. BYAM, of Rochester, in the county of Monroe and State of New York, have invented a certain new and useful Improvement in Sash-Lifts; and I do hereby declare that the following is a full, clear, and exact description of the same, reference being had to the drawings accompanying this application.

10 My improvement relates to devices attached to sashes for the purpose of raising and lowering the same. The side piece of an ordinary sash is provided with a bevel at the edge; and the object is to so construct the sash-lift that, 15 while it fits this bevel or incline, it still stands within the plane of the surface of the sash, so that one sash can run past the other in being raised and lowered without impediment from the sash-lift. It is particularly applicable to 20 the upper sash, which has to run up and down behind the lower one; but it is also applicable to the lower sash, and is of advantage where screen-frames and inside blinds are used, as it does not interfere with the raising 25 and lowering of the sash when such screens and blinds are employed.

In the drawings, Figures 1 and 2 are perspective views of the device, showing "rights" and "lefts." Fig. 3 is a perspective view of 30 one corner of the meeting-rails of two sashes with the device applied to the upper sash. Fig. 4 is a horizontal section of Fig. 2 in line $\alpha\alpha$, looking downward.

A and A' indicate the improved sash-lift in 35 rights and lefts. Each of these devices is a finger-piece of right-angled form, and provided with a screw-hole, by which it can be screwed to the sash. The horizontal part a projects inward and forms the finger-piece for raising 40 the sash. The vertical part b rests against the inner edge of the vertical side piece of the

sash, and is secured thereto by a screw, as shown.

The inner edge of the sash is made with an inclined bead or bevel, c ; hence, if the sash-lift A were made with a square back side, the finger-piece a would project outward at an angle to the sash and would stand out beyond the face of the same, so that if applied to the upper sash it could not run up and down behind the lower one, or if applied to the lower sash it could not run behind inside blinds or screen-frames placed in the windows. To remedy these difficulties the back of the sash-lift A is made angular, as shown at d , so that when fitted to the inclined bead or bevel c the arm a of the device will stand parallel with the window and within the plane of the surface of the sash, as shown in Fig. 4.

By the means above described the device answers all the purposes of an effective sash-lift, and enables the upper sash to run up and down behind the lower one, or the lower sash to run up and down behind screens and blinds without impediment.

Having described my invention, what I claim as new, and desire to secure by Letters Patent, is—

As an improved article of manufacture, a sash-lift consisting of a right-angled finger-piece having an inclined back to fit the inclined bead or bevel of the sash and allow the finger portion to rest parallel with the face of the sash and within its surface, as and for the purpose specified.

In witness whereof I have hereunto signed my name in the presence of two subscribing witnesses.

E. C. BYAM.
